(57) **CLAIM**

The ornamental design for a three wheel rollator, as shown and described.

DESCRIPTION

[FIG. 1 is a front, perspective view of a three wheel rollator in accordance with the present design;]

[FIG. 2 is a front view thereof;]

[FIG. 3 is a rear view thereof;]

[FIG. 4 is a right side view thereof;]

[FIG. 5 is a left side view thereof;]

[FIG. 6 is a top view thereof; and,]

[FIG. 7 is a bottom view thereof.]

FIG. 8 is a front, perspective view of a three wheel rollator in accordance with the present design;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The broken lines shown in the drawings illustrate portions of the three wheel rollator that form no part of the claimed design.

1 Claim, 14 Drawing Sheets

Matter enclosed in heavy brackets [ ] appears in the original patent but forms no part of this reissue; matter printed in italics indicates the additions made by reissue.
